UNITED STATES PATENT OFFICE.

THOMAS REED BUTMAN, OF CHICAGO, ILLINOIS.

FLUE-CLEANER ROD.

SPECIFICATION forming part of Letters Patent No. 425,593, dated April 15, 1890.

Application filed February 6, 1890. Serial No. 339,393. (No model.)

To all whom it may concern:

Be it known that I, THOMAS REED BUTMAN, of Chicago, in the county of Cook and State of Illinois, have invented certain new and

5 useful Improvements in Flue-Cleaning Rods; and I do hereby declare that the following is a full, clear, and exact description of the invention, which will enable others skilled in the art to which it appertains to make and
10 use the same, reference being had to the accompanying drawings, and to the letters of reference marked thereon, which form part of this specification.

This invention relates to certain improvements in flue-scraping rods for steam-boilers.

It is well known that the flues of steam-boilers when in operation become foul with soot and ashes, thereby impairing their capacity for absorbing heat as well as retarding the draft; hence the flues have to be often brushed and cleaned out while the boilers are in use. Ordinarily suitable lengths of gas-pipe are employed to operate the brush, and when the boilers are so located that a wall, bulk-head, or machinery prevents the use of a single rod of the full length of the flues, a solid rod of iron is usually employed formed in sections connected together by looped or hooked ends. The rods thus joined become
25 easily locked together, and consequently require two operators to successively use them. Further, the diameter of these rods is so small that they are difficult to grasp firm enough to force through the fouled flue, and also they
30 become heated by contact with the hot walls of the flues, thereby rendering them difficult to handle.

The object of my invention is to provide a cheap, simple, strong, and durable rod over-
40 coming these disadvantages, and which will be composed of two or more lengths of wood or other light and strong non-conducting material, the lengths or sections of which are joined together by one or more universal
45 joints, so that the rods can be used around angles and between partitions to clean the flues, and when out of use can be folded up with the sections or lengths lying parallel and at right angles to the connecting-link of the
50 joint; and a further object of the invention is to provide a flue-scaper composed of several sections so united by a connecting-link that

the rod-section carrying the brush can be operated in a higher or lower plane than the handle-section or in a plane at any angle 55 thereto.

These objects are accomplished by and this invention consists in certain novel features of construction and in combinations of parts, more fully described hereinafter, and particularly pointed out in the claims.

Figure 1 is an elevation of the preferred construction of rod. Fig. 2 is a similar view of another construction of rod. Figs. 3 and 4 are details of the connecting-links of the 65 constructions of Figs. 1 and 2, respectively. Figs. 5 and 6 are details of the sockets of Figs. 1 and 2, respectively. Fig. 7 is a section of the brush-holding ferrule.

In the drawings, the reference-letter *a* indicates several lengths or rods of strong durable wood or other light strong non-conducting material. One end of one length or rod forms the handle *b*, while the opposite end of the other rod or section is provided with a 70 metal ferrule *c*, provided with a bore to receive the end of the rod, and with a screw-threaded hole *d* tapped in its outer end to receive the shank or holder of the brush. This ferrule is provided with a series of longitudinal 75 radially-projecting wings *e*, the outer edges of which are adapted to run on and bear against opposite sides of the inner surface of the flue and center the brush therein and prevent the brush from dropping down 80 to the lower side of the flue when pushed out of the inner end of the flue, thereby rendering the operation easy and preventing wear on the flue and brush, for in some constructions when the brush was pushed through 85 the flue from one end it would pass through the flue and out at the opposite end and drop down, so that the rod would rest on the lower side of the flue. Consequently it was very difficult to draw the brush back into the flue, 90 and was very wearing on brush and end of tube.

The inner ends of the two rods or lengths are fitted with ferrules or sleeves, the outer ends of which form cases or sockets *h*, loosely 100 inclosing the balls *f f*, rigid on the opposite ends of the short link or rod *g*. Each ferrule and case is formed in two longitudinal halves or sections fitting on opposite sides of the

rod and secured together and to said end by rivets, bolts, or the like passed through the ferrule-sections and the end of the rod; hence when the rod is being put together the ball 5 *f* on one end of link *g* is placed in a socket-section, and then the other section is placed thereon and secured, thus forming the complete socket and loosely confining the ball therein. The edges of these sockets are provided with one or more pairs of inwardly-extending longitudinal slots *i*, of such size as to allow the connecting-link *g* to fit therein and lie at right angles to the rod. By this construction the rods *a* can be folded together 10 parallel and the link *g* will lie at right angles to said rods and will lie in slots *i* in the ball-sockets. The construction of Fig. 1 shows the ferrule-socket *h* provided with a plurality of slots *i*, so that the rods can be folded parallel in any direction and from any side, and the curved tapered fingers between the slots are provided with exterior re-enforcing ribs *j* to strengthen the fingers and permit cutting the slots. These re-enforcing 15 ribs can be dispensed with for some cleaning rods, as the socket can be made of cast-steel or other strong material.

In Fig. 2 the ferrule-sockets are provided with two oppositely-located slots, so that the 20 rods can fold together in two directions only, the connecting-link having cross-bars *k* at its ends, which cross-bars are journaled in the sockets to allow the link to swing in two directions. This jointed rod is adaptable for 25 other purposes where a jointed folding rod is desired. For instance, by having a plurality of rods connected by either of the joints here mentioned and providing one rod with a hook or attachment for holding the wire the rods 30 can be successfully used for pulling wire through conduits.

It is evident that various changes might be resorted to in the form and arrangement of the parts described without departing from 35 the spirit and scope of my invention; hence I do not wish to limit myself to the precise construction herein set forth.

What I claim is—

1. A flue-scraper rod consisting of two or 40 more rigid sections, rigid ferrules on the adjoining ends of said sections, and a link loosely connecting said sections to allow the

same to fold parallel and swing freely, said link at its ends being loosely secured to the outer ends of said ferrules, substantially as 55 described.

2. A flue-scraper rod consisting of two or more sections, longitudinally-divided ferrules rigidly secured on the adjoining ends of said sections, the outer ends of said ferrules being slotted or bifurcated, and a straight link loosely connecting said sections, at its ends loosely secured in said slotted ends of the ferrules, whereby the sections can be folded together or used in different planes and 60 angles.

3. The combination, in a flue-cleaner, of two or more rods having sockets on their ends provided with a plurality of slots, and a link connecting said ends and confined at its 65 ends in said sockets, whereby the rods can be folded together parallel and at right angles to the link, substantially as described.

4. A folding flue-scraping rod composed of two or more wooden rods, ferrules on their 70 ends provided with sockets, a link connecting said rods and at its ends loosely confined in said sockets, and a ferrule on the end of one rod to receive the brush, substantially as described.

5. A flue-scraper rod formed in sections, the sections having separable ferrules rigidly secured on their ends and provided with rigid end sockets, and the link loosely connecting 75 each pair of rods and provided with balls on its ends loosely confined in said sockets to allow the sections free and universal swing, substantially as described.

6. Two rods having ferrules rigidly secured on their ends, forming rigid end sockets provided with a plurality of longitudinal slots, 80 re-enforcing ribs on the tapered fingers separating said slots, and the link having balls at its ends loosely confined in said sockets and connecting the rods, substantially as described.

In testimony that I claim the foregoing as my own I affix my signature in presence of two witnesses.

THOMAS REED BUTMAN.
